DESIGN FOR A DRESS

Lee Friend and Emanuel Wieder, New York, N. Y.

Application June 23, 1939, Serial No. 85,641

Term of patent 3½ years

To all whom it may concern:

Be it known that we, Lee Friend and Emanuel Wieder, citizens of the United States of America, residing in New York city, in the Borough of Manhattan, county and State of New York, have invented a new, original, and ornamental Design for a Dress, of which the following is a specification, reference being had to the accompanying drawing, forming part thereof, wherein, new design, with the hood portion partly detached from the dress, disclosing the collar.

We claim:

The ornamental design for a dress, substantially as shown and described.

LEE FRIEND.
EMANUEL WIEDER.
